UNITED STATES PATENT OFFICE

2,077,405

SANDING BLOCK

Conrad Christian Enge, Petersburg, Territory of
Alaska

Application March 7, 1936, Serial No. 67,724

5 Claims. (Cl. 51—187)

The invention relates to a sand paper holder and more particularly to a sanding or polishing block.

The primary object of the invention is the provision of a block of this character, wherein the same carries clamps so that an emery cloth or sand paper can be conveniently and easily clamped upon the block for the use of the same in cleaning woodwork or other materials needing sanding or polishing, the block being of novel construction and will firmly and securely hold the emery cloth or sand paper.

Another object of the invention is the provision of a block of this character, wherein the same carries a resilient covering piece so that when sand paper or emery cloth is attached to the block a smoother finish to a piece of work is assured and also eliminates premature wear of the emery cloth or sand paper.

20 A further object of the invention is the provision of a block of this character, which is simple in construction, thoroughly reliable and effective in its purpose, strong, durable and inexpensive to manufacture.

25 With these and other objects in view, the invention consists in the features of construction, combination and arrangement of parts as will be hereinafter more fully described, illustrated in the accompanying drawing, which discloses the 30 preferred embodiment of the invention and pointed out in the claims hereunto appended.

In the accompanying drawing:

Figure 1 is a top plan view of a block constructed in accordance with the invention and partly in section.

Figure 2 is an end elevation thereof.

Figure 3 is a longitudinal sectional view taken on the line 3—3 of Figure 1 looking in the direction of the arrows.

40 Figure 4 is a sectional view on the line 4—4 of Figure 1 looking in the direction of the arrows.

Figure 5 is a perspective view of one of the gripping balls employed with the block.

45 Figure 6 is a view similar to Figure 1 showing a modified form.

Figure 7 is a sectional view on the line 7—7 of Figure 6 looking in the direction of the arrows.

Figure 8 is a fragmentary horizontal detailed 50 sectional view taken approximately on the line 8—8 of Figure 9.

Figure 9 is a sectional view on the line 9—9 of Figure 8.

Similar reference characters indicate corresponding parts throughout the several views in 55 the drawing.

Referring to the drawing in detail, particularly Figures 1 to 5 inclusive, A designates generally a block preferably made from wood having a sunken area in its top to provide upwardly divergent ledges 10 while about the bottom working face 5 and opposite longer sides of the block A is trained a resilient piece 11, its side edges being carried on to the ledges 10 and made secure thereto by metal retaining strips 12, these being secured in place by fasteners 13.

10 Located in the sunken top of the block A is a plate 14 of metal, the same being of the required width and length and is made secure or fixed by fasteners 15 which are driven into the block A through the top thereof. Riveted to this plate 15 are latching cams 16, these being adapted to swing on the rivets 17 which function as pivots therefor for biting engagement with a pair of clamping balls 18 swingingly supported upon pivots 19 carried in downturned ends 20 of the plate 14 and accommodated within insets 21 provided in opposite ends of said block A. These balls 18 are adapted to be swung to a gripping position to engage with overlapping edges 22 with relation to the strips 12 of a piece of sand paper 23 which is adapted to be wrapped about the block A and overlie the resilient piece 11 which constitutes a backing for said piece of sand paper 23.

20 The latching cams 16 are formed with finger engaging extensions 24 so that they can be readily manually manipulated for shifting the same into latching or unlatching position. These latching cams have serrated edges 25 so as to assure a positive and firm grip upon the balls 18 to avoid slipping of these latching cams when thrown into latching position to hold the balls in clamping engagement with the overlapping edges 22 of said piece of sand paper 23.

25 The sand paper 23 when wrapped about the block A will be backed by the resilient piece 11 40 for the cushioning of such sand paper 23 in the use of the block for sanding purposes.

In Figures 7, 8 and 9 of the drawing there is shown a slight modification wherein the latching cams 26 are formed with externally ratchet faced hubs 27, these being journaled on pivot bolts 28 mounted in a housing 29 beneath the plate 30 which is similar to the plate 14 and within this housing 29 is a ratchet spring 31 the same being adapted to play against the ratchet faced hubs 27 of the cams 26 so that ratchet action is had when these cams 26 are moved into latching or unlatching positions, the ratchet action being effective in throwing the cams 26 in either direction.

55

It is preferable to have the bails 18 provided with a central nib 32 for biting engagement with the serrated edges 25 of such cams 16.

It is, of course, understood that in lieu of the sanding paper 23 other abrasive material may be used, as for example, emery cloth serviceable for polishing purposes.

While it has been stated that preferably the block A is made from wood the same may be made from metal, such as aluminum, if found desirable.

What is claimed is:

1. As an article of manufacture a block having a sunken top providing angled ledges opposite each other at the sunken top, a pair of latching cams swingingly supported in the sunken top, and clamping bails swingingly carried by the block and movable between the cams and said ledges for the clamping of abrasive material when wrapped about the block.

2. As an article of manufacture a block having a sunken top providing angled ledges opposite each other at the sunken top, a pair of latching cams swingingly supported in the sunken top, clamping bails swingingly carried by the block and movable between the cams and said ledges for the clamping of abrasive material when wrapped about the block fixed thereon, and a resilient backing on the block for said abrasive material.

3. As an article of manufacture a block having a sunken top providing angled ledges opposite each other at the sunken top, a pair of latching

5 cams swingingly supported in the sunken top, clamping bails swingingly carried by the block and movable between the cams and said ledges for the clamping of abrasive material when wrapped about the block fixed thereon, a resilient backing on the block for said abrasive material, and ratchet means coacting with said cams.

4. As an article of manufacture a block having a sunken top providing angled ledges opposite each other at the sunken top, a pair of latching cams swingingly supported in the sunken top, clamping bails swingingly carried by the block and movable between the cams and said ledges for the clamping of abrasive material when wrapped about the block fixed thereon, a resilient backing on the block for said abrasive material, ratchet means coacting with said cams, and serrations formed at the working edges of said cams.

5. As an article of manufacture a block having a sunken top providing angled ledges opposite each other at the sunken top, a pair of latching cams swingingly supported in the sunken top, clamping bails swingingly carried by the block and movable between the cams and said ledges for the clamping of abrasive material when wrapped about the block fixed thereon, a resilient backing on the block for said abrasive material, ratchet means coacting with said cams, serrations formed at the working edges of said cams, and spurs on the bails cooperating with said serrations.

CONRAD CHRISTIAN ENGE.
